ELECTRODE SECURING MEANS

Walter L. Krahl, Emporium, Pa., assignor to
Sylvania Electric Products, Inc., a corporation
of Massachusetts

Application June 7, 1946, Serial No. 674,959

11 Claims. (Cl. 250—162)

1

This invention, while relating broadly to a structural fabrication of metallic and non-metallic parts, has more particular reference to a means for securing metallic parts of electronic devices to insulating supports in accurate relationship to one another.

Specifically, the invention relates to the assembly of a cathode ray tube gun and to a new and novel means whereby electrodes, both cylindrical and disc-like, and deflection plates, are rigidly clamped precisely in predetermined relative arrangement to a plurality of supporting columns or posts, such as tubular ceramic rods regularly spaced in a circle concentric with the axis of the gun.

In electronic devices of this character different clamping methods have been used which have not been entirely satisfactory in that true parallel spacing and axial alignment of the electrodes are difficult to obtain. One such method now in common use is to employ eyelets as the securing means, these eyelets being pressed into the electrodes, as sleeves to slidably receive the supporting columns, and later crimped into binding engagement with such supports by means of a special tool designed for that purpose.

Pressure of the tool in the crimping operation and the depth of the grooves formed in the sleeves cannot be too greatly varied owing to the brittleness of the ceramic rods and their possibility of being broken. Yet, there must of necessity be a tight fit of the sleeves on the rods due to having to center the electrodes over a plurality of supports, and to the necessity to hold the electrodes rigidly. Because of variations in ceramics the binding action of eyelets to these ceramics is not uniform and in some instances it is so tight as to break the ceramics while in others the clamping is not secure. Furthermore, torsional strains that may be exerted by application of a crimping tool have a tendency to throw the parts out of alignment.

One of the principal objects of the present invention, therefore, is to eliminate the use of eyelets and substitute securing means which will assure a uniform and rigid clamping of all metal-to-ceramic connections.

Another object of the invention is to provide an improved and more rigid cathode ray tube gun in which the electrodes are accurately spaced and aligned in their relationship one with another, and in the assembly of which it is not required to use either axial or torsional forces, the only pressure applied in clamping the electrodes in place being in lines radially thereof.

2
In order to accomplish the aforesaid objects, I make use of a clamping means of like construction and application for all parts which are to be secured to the ceramic insulating and supporting posts, in that each clamp comprises complimentary parts providing a split collar surrounding the supports and with the half portions terminating in opposing flanges to be welded together.

- 10 10 The metallic parts of the assembly are die-formed and it is a further object of the invention, in providing clamping means of the character described, to form, in most instances, one part of the member to be supported. Thus semi-cylindrical grooves in these half portions of the clamps are accurately positioned with relation to one another and to the center of the member of which they are a part. These grooves are of such a radius that their side walls snugly fit the ceramic posts and provide accurately aligned locating means for the supports when the parts to be secured thereto are set up in an assembly fixture.
- 15 20 25 And, a further object of the invention is to permit assembly of an electronic device of the character described with greater ease, more expeditiously and with simpler tools than required with certain methods heretofore used.

30 30 To these and other ends the invention consists of certain parts and combinations of parts as will be fully set forth in the following description and particularly defined in the appended claims.

35 35 The accompanying drawings illustrating the invention as embodied in the gun of a cathode ray tube and forming a part of the specification are as follows:

40 40 Fig. 1 is an end view and Fig. 2 is a view in side elevation of the gun, parts of the end pair of deflection plates being broken away in Fig. 1 to more clearly bring out the invention.

45 45 Fig. 3 is a sectional view on line 3—3 of Fig. 2. Fig. 4 is an enlarged sectional detail on line 4—4 of Fig. 3.

50 55 Fig. 5 is a view from the underside of Fig. 4, but showing the clamping means in full. Fig. 6 shows a cathode ray tube in side elevation, a portion of the envelope being broken away to show a part of the gun mounted therein.

Fig. 7 is an enlarged fragmentary section taken on line 7—7 of Fig. 2, and Fig. 8 is a sectional detail on line 8—8 of Fig. 7.

55 In the drawings similar reference numerals

refer to similar parts throughout the several views.

The numerals 1, Fig. 6, represents the envelope of an electronic tube of the cathode ray type and within the reduced, straight end of which the gun, indicated as a whole at 2, is arranged and mounted in the usual manner, as by lead-in wires sealed into a glass header not shown, the base being indicated at 3 and terminal pins at 4.

The gun, in this instance, is shown as including a plurality of axially spaced disc-like electrodes, 5, 6, and 7 which are substantially similar in that they are of like diameter and have flat portions of comparatively large area in which a series of holes 8 is arranged in a concentric circle. The disc 6 is shown as having a centrally disposed depending cylindrical projection 9 while pressed upwardly from the plane of disc 7 is a shorter cylindrical part 10.

Coaxial with the discs 5, 6, and 7 but spaced below them, that is with respect to Figs. 2 and 6, and likewise axially spaced from each other, are a plurality, in this instance two, cylindrical electrodes 11 and 12 to the outer face of which collars 13 are welded, these collars being at right angles to the cylinders and formed as are the discs of comparatively thin sheet stock but of a diameter less than that of the discs 5, 6, and 7. These cylindrical electrodes, according to their lengths, may be provided with one or more of the collars 13, as shown.

Between the disc electrodes 5 and 6 there is a pair of vertically arranged deflection plates 14 spaced equidistant from the axial center of the discs and above the disc 5 is a similar pair of plates 15, but disposed at right angles to the plate 14.

The disc 5, referring to Fig. 1, has a relatively large central opening 16 while the disc 7 has a relatively small aperture in its center which must be in accurate axial alignment with similar apertures in discs secured within the cylindrical parts 9, 11, and 12. One of these apertures which are provided for the passage of the electron beam is shown at 18 in the disc 17 in Fig. 3. These discs must be held in true parallelism and in definite spaced relationship with respect to adjacent discs.

The metallic parts above enumerated are insulatingly supported in this instance by four parallel columns 19 regularly spaced angularly in a circle concentric with the axial center of the gun. These columns are, preferably, cylindrical and comprise tubular ceramic rods, the means employed for securing the metal parts to the ceramics constituting the present invention.

The die-formed discs 5, 6, and 7 are flat and in the area within the circle of holes 8 substantially rectangular sections 20, as shown for one of the discs in Figs. 7 and 8, are cut in the blanking operation along three sides and in the forming are bent outwardly at right angles along their inner longitudinal edges, these sections, also being drawn to the contour shown, that is, to provide for each a semi-circular groove portion centrally disposed and terminating in side flanges 21 the outer faces of which lie in a plane coincident with the center of the groove. Openings 22, are thus provided in the discs 5, 6, and 7 which receive the rods 19 and the inner faces of the grooved portions are of a radius to snugly fit the rods.

Thus, there are formed the inner members of the disc-to-ceramic securing means, the outer

complementary members or anchoring means 23 being formed from strips of a width equal to the depth of the sections 20 and having outwardly pressed grooved portions terminating in flanges 24 opposed to corresponding flanges 21 and which by fastening means, as spot welding, are attached to the flanges 21. The radius of the grooved portions of the anchor strips is the same as that for the grooved portions of the sections 20, that is to fit the ceramics snugly, but the included angle is slightly less than 180° so that when the flanged ends 21 and 24 are welded the grooved portions of the sections 20 and the anchor strips 23, forming split collars practically encircling the rods 19, will be drawn into secure binding engagement with the rods.

In blanking out the collars 13 they are provided with radially projecting rectangular portions which in the forming operation are bent at right angles along lines tangential to the peripheral edge of the collars to form the inner members 25 of clamping means for the cylindrical electrodes 11 and 12, these members, like the section members 20, having semi-circular grooved portions to fit the rods 19 and which terminate in flanges 26. Complementary to the members 25, as the clamping parts for encircling the outer portions of the rods 19, are anchor strips 23 the flanges 24 of which are welded to the flanges 26 in the same manner as the corresponding parts of the like anchor strips for the disc electrodes are attached to the flanges 21 of the section members 20.

For supporting the pairs of deflection plates 14 and 15 and securing them to the ceramic columns, brackets are welded to the outer faces of the vertical portions of these plates and include outwardly extending arms 27 which, adjacent their outer ends, are formed with semi-circular grooved portions to also snugly fit the rods 19. Likewise, anchor strips such as indicated at 23a, form the complementary parts of these clamps and have their flanges 24a welded to the opposing extensions or flange portions 28 of the arms 27.

In assembling the gun, a suitable fixture is provided for holding the disc electrodes 5, 6, and 7, the cylindrical electrodes 11 and 12 and the pairs of deflection plates 14 and 15 in proper relationship. Four ceramic rods 19 are then placed in position, and it will be observed that with the centers of the grooved portions of the parts 20, 25, and 27 of corresponding clamps in axial alignment, these portions will function as locating means for the rods. One of the anchors 23 is then placed opposite each of the sections 20 and members 25 and an anchor bracket 23a against the grooved outer end portion of each arm 27, so that respective grooved portions are in contact with the ceramics, and the flanges of anchors 60 are welded to the corresponding opposite flanges on the members to which the anchors are to be attached. Thus, since the diameters of the complementary clamping members, comprising the split collars for securing the discs, the cylinders supporting collars and the deflection plates, were selected to fit the ceramics tightly, and since the anchors 23 and anchor brackets 23a must be bent slightly to be welded in place, it will be obvious that the ceramics will be uniformly gripped and securely held. It will also be obvious that the ceramics will be forced toward the center of the discs and collars as far as the respective grooved portions of the parts 20 permit. Therefore the disc electrodes and cylindrical electrodes will be concentrically secured if these parts, with the de-

lection plates, are accurately aligned and if the ceramic supports are straight. And, it will also be noted that this method of securing discs and cylinders to ceramics has no tendency to change the spacing between the flat sections of these collars and discs, as is the case with the use of eyelets and certain other methods of clamping now in use.

Although I have shown and described particular embodiments of my invention, I do not desire to be limited to the embodiments described, and I intend in the appended claims to cover all modifications which do not depart from the spirit and scope of my invention.

What I claim is:

1. Means for rigidly securing two frame members to each other in accurate predetermined relation, one of said members being of sheet material and including a flat portion and the other a supporting post, said securing means comprising complementary clamping members formed with opposing channels the walls of which are in gripping engagement with said post, one of said clamping members being integral with the flat portion of said sheet member, with its channel extending angularly from said flat portion and providing a locating means for said post, and said other clamping member being attachable to said first named member on opposite sides of said post and providing an anchoring means for the post.

2. Means for rigidly securing a disc-like member of sheet material to a supporting post in predetermined angular relation to each other, said securing means comprising complementary clamping members formed with opposing channels the walls of which are in gripping engagement with said post, one of said clamping members being a sectional portion bent outwardly from the body of said disc-like member parallel to said post, with its channel providing a locating means for the post, and said other clamping member being attachable to said first named member on opposite sides of said post and providing anchoring means for the post.

3. Means for rigidly securing a disc-like member of sheet material to a supporting post in predetermined angular relation to each other and at the peripheral edge of said disc-like member, said securing means comprising complementary clamping members formed with opposing channels the walls of which are in gripping engagement with said post, the inner one of said clamping members being a radially projecting portion bent from the plane of said disc-like member parallel to said post, with its channel providing a locating means for the post, and said other clamping member being attachable to said first named member on opposite sides of said post and providing anchoring means for the post.

4. Means for securing a disc-like member of sheet material to a plurality of supporting posts parallel to each other and at right angles to said disc-like member, said posts being cylindrical with their axes located on radii from a common center and regularly spaced on a circle concentric with said center, said securing means comprising, for each post, a sectional portion pressed from the plane of said disc-like member and formed intermediate its ends with an inwardly pressed semi-circular groove of a radius to snugly fit one of said posts and with its center line coaxial with such post, a flange on said sectional portion each side of said groove, an anchor strip having a groove opposing that of said sec-

tional portion, and flanges on said anchor strip engaging and attached with said strip under tension to corresponding ones of said flanges on said sectional portion.

5. Securing means as recited in claim 4 characterized by the radius of the grooves in said anchor strips being the same as that of the grooves in said sectional portions and by the included arc of the groove in each of said strips being slightly less than 180°.

6. Means for rigidly securing a plurality of die-formed sheet metal discs to a plurality of cylindrical supports of an electrically insulating material, with said discs precisely spaced axially of each other in true parallelism and with said supports at right angles to said discs and regularly spaced in a circle concentric therewith, said securing means comprising clamps including sectional portions bent along one edge from the plane of each disc and formed intermediate their ends with inwardly pressed semi-circular grooves of a radius to snugly fit said supports, said supports extending through openings in said discs formed by depressing said sectional portions, flanges on said sectional portions in planes coincident with the diameters of said supports, anchor strips formed with grooves opposing the grooves in said sectional portions, and flanges on said strips the inner faces of which are welded to the outer faces of the corresponding flanges on said sectional portions, the included arc of the grooves in said anchoring strips being slightly less than 180°.

7. In an electronic device, a disc electrode, a cylindrical electrode having a surrounding collar including a disc-like portion attached to it, a plurality of ceramic posts regularly spaced in a circle concentric with said cylindrical electrode for insulatingly supporting said electrodes concentrically and in predetermined axially spaced relation to each other, said disc and said collars having projecting portions bent normal to the planes of said disc-like portions, said projecting portions being formed intermediate their ends with inwardly pressed grooves forming arcs of a circle of radius permitting the walls of said grooves to snugly fit said ceramic posts, aligned grooved portions of said two electrodes being locating means for said posts, flanges on said projecting portions at opposite sides of said grooves, and means cooperating with said projecting portions for rigidly clamping said disc and said collar, respectively, to said posts comprising anchor strips having grooves to receive the outer portions of said posts and including flanges welded to opposing flanges on said projection, the included arc in at least one of each of the pairs of grooved members being less than 180°.

8. A cathode ray tube gun assembly including a disc electrode and a pair of deflection plates spaced apart equidistant from the axial center of said disc, a plurality of ceramic posts at right angles to said disc and regularly spaced in a circle concentric therewith, said posts being the means for supporting said disc and said plates in axially spaced relation and extending through openings provided in said disc, and means for rigidly clamping said disc and said plates to said posts comprising split collars encircling said posts and formed of complementary sections including flanges extending laterally from the encircling collar portions at opposite sides of the posts, the opposing flanges of respective collars being welded together and with the included arc of at least one section of each collar being slightly less than

180°, one section of each of said plate clamping collars being integral with and extending angularly from the outer face of said plate, and one section of each disc clamping collar being a rectangular portion bent along one edge from the plane of said disc and at right angles thereto, the outward bending of said portions providing the said disc openings for said posts.

9. A cathode ray tube gun assembly including in its structure a disc-like electrode, a cylindrical electrode comprising a cylinder and a surrounding collar of less diameter than said disc electrode, a pair of deflection plates, a plurality of ceramic rods for supporting the said parts with said electrodes in axial alignment and with said disc, collar and deflector plates in predetermined spaced relation to each other, said disc and collar being parallel and said rods arranged at right angles thereto and regularly spaced in a circle concentric therewith, and means for rigidly securing said electrodes and said plates to said rods comprising arms extending laterally from the outer side faces of said plates, rectangular sectional portions bent along one edge from and at right angles to said disc and providing openings for said rods, like portions forming radial projections on said collar and bent at right angles on lines tangential to its peripheral edge, semicircular grooves pressed from the plane of said arms and inwardly from said disc sections and said collar projections, flanges along the side edges of all of said grooves, said grooves being of a radius to snugly fit said rods and providing locating means for the rods, respective ones of said grooved parts having their grooves in axial alignment, and anchoring means for said rods comprising metal strips grooved to

form clamping members complementary to said grooved arms, rectangular sections and collar projections and including side flanges which by welding are attached to respective opposing ones of said first named flanges, the included arc of the grooves in said anchor strips being slightly less than 180°.

10. In an electron discharge device, an electrode comprising a generally flat part of sheet metal, 10 an insulator, and means to secure said electrode and said insulator together comprising a channel extending transversely from said flat part and a strap secured to said channel, said insulator being gripped between said channel and said strap.

11. A cathode ray tube having an electrode comprising a generally flat sheet metal support and a transversely extending active portion, an insulating post transverse to said support, and means to secure said post and said electrode together comprising a channel extending transversely from said support and a strap secured to said channel, said insulator being gripped between said channel and said strap.
